UNITED STATES PATENT OFFICE.

PORTER C. REED, OF KINGSTON, MASSACHUSETTS.

NAIL-MACHINE.

SPECIFICATION forming part of Letters Patent No. 313,108, dated March 3, 1885.

Application filed February 27, 1884. (No model.)

To all whom it may concern:

Be it known that I, PORTER C. REED, of Kingston, in the county of Plymouth, in the State of Massachusetts, have invented certain new and useful Improvements in Nail-Machines, of which the following is a specification.

My invention relates to that class of machines for making tacks in which the nail-blank is gripped by its edges, the objects being to substitute for the two stationary bed-dies that have usually been placed in machines a single thick die, part of the face of which is scored to receive the blank tack or nail, the other part being beveled away, so as not to interfere with the free delivery of the tack or nail when completed; also, to hold the blank by an upright nipper until gripped by the moving die, and to so arrange the nipper and its connecting parts that it can be adjusted for receiving nails of different sizes. I attain these objects by the mechanism illustrated in the accompanying drawings, in which—

Figure 1 is a side elevation. Fig. 2 is a vertical longitudinal section of the machine. Fig. 3 is a planned section, and Fig. 4 is a perspective view of details. Fig. 5 is a plan showing my improved bed-die. Fig. 6 is a side elevation of the same. Fig. 7 is a detail showing the working-face of die F.

In the drawings, A represents the frame of the machine, and D the main shaft, to which the operating-cams are attached.

D', Fig. 1, is a crank-disk, which operates through its crank-pin d the link D², which in turn, operating the lever D³, imparts motion to the cutting-jaw D⁵. The moving knife H', Figs. 2 and 4, is attached to the jaw D⁵, while the stationary knife H is affixed to the frame of the machine.

E', Figs. 1 and 3, is a lever-frame which operates the header E³.

All the parts above referred to are old, being elements of the well-known Reed machine, patented to Jesse Reed, August 14, 1811.

I will now describe the parts that I consider new.

In some of the ordinary machines there are placed immediately under the bed-knife H, Figs. 2 and 4, two pieces of steel, one called the

“bed-die,” and the other the “back piece,” the bed-die being provided with a groove in which the blank is held in the process of heading, and the back piece being provided with an angular groove on the same line as the groove in the bed-die, the only use of the back piece being to hold the blank after it is cut off until the gripping and heading devices have time to operate.

In my invention I dispense with the back piece altogether and substitute for it and the bed-die one thick die, F, made in plan, as shown at Fig. 5, and in elevation, as shown at Fig. 6, the end being beveled, as indicated at F² F³, Fig. 5, and grooved, as shown at F', Fig. 6, the groove F' extending from F⁴ to F² of Fig. 5—that is, about the length of the nail-blank that is being worked. The nipper L², Fig. 4, seizes the nail at right angles and presses it against the bed-die F, Fig. 5, the nipper acting on the blank at a point near F', leaving room for the moving die C', Fig. 4, to come forward and hold the blank firmly against the bed-die F until the nail is headed. The nipper L², Figs. 1, 2, and 4, is supported by a base-piece, L, said base-piece L being adjustable by the screw L', Fig. 2. The nipper L² is made of thin metal, so that it may bend and adapt itself to the adjustment of the screw L'. Thus the angle between the upper end of the nipper L² and the bed-die F can be varied so as to hold the blank in the best possible position. This nipper L² is operated by a spring-lever, L³, Fig. 4, a projecting arm, L⁶, of which comes in contact with the upper end of L².

L⁴ is a link which connects the spring L³ with the cam-lever L⁵, Fig. 4, the cam-lever L⁵ being operated by a cam on the main shaft D. (Not shown.)

I am aware of Patent to Haddock, No. 172,427, and therefore lay no claim to the construction therein shown and described.

I claim—

1. The combination, with the moving die C and bed-die F, of the nipper L², its adjustable base-piece, spring-lever L³, link L⁴, and cam-lever L⁵, substantially as and for the purpose herein described.

2. In a machine for making edge-gripped

nails, the combination of a vertical nipper, its adjustable base-piece, and moving die C with a single thick die adapted to take the place of a die and back piece, substantially as and for the purpose set forth.

5 3. In a nail-machine for making edge-gripped nails, a single thick die, F, provided

with a groove in its working-face for holding the blank, and having a portion of its face beveled, substantially as described.

PORTER C. REED.
